(57) **CLAIM**

The ornamental design for an LED linear replacement lamp design, as shown and described.

DESCRIPTION

FIG. 1 is a top perspective view of an LED linear replacement lamp showing our new design;

FIG. 2 is a bottom perspective view thereof;

FIG. 3 is a bottom view thereof;

FIG. 4 is a side view thereof;

FIG. 5 is a top view thereof; and,

FIG. 6 is an end view thereof.

The broken lines in FIGS. 1-6 are for illustrative purposes only and form no part of the claimed design.
